RECIPROCATING CONTACT SWITCH

Joseph F. Frese, Baltimore, Md., assignor to The Monitor Controller Company, Baltimore, Md., a corporation of Maryland

Application August 30, 1945, Serial No. 613,624

5 Claims. (Cl. 200—16).

1

My invention relates broadly to electric switches and more particularly to an improved construction of momentary contact oil switch.

One of the objects of my invention is to provide an improved construction of oil switch of the momentary contact type for power wiring in which wire terminals are maintained above a predetermined oil level and a momentary contact is effected within an oil immersed bath.

Another object of my invention is to provide a construction of momentary contact oil immersed switch in which contacts operating within an oil submerged bath may be readily removed and replaced for renewing contacts which may become injured or worn in use.

Another object of my invention is to provide an improved construction of oil switch in which the contactors and contact elements of the switch may be readily replaced without replacing the switch as a whole.

Still another object of my invention is to provide an arrangement of movable contactor system for oil immersed switches in which disc elements are employed and which may be angularly adjusted in position to present a fresh contact surface to coating contacts to insure good electrical conductivity throughout the operating cycle of the switch.

Still another object of my invention is to provide a construction of oil switch including an oil containing casing which may be readily mounted on a standard wiring outlet box in such manner that condensation which may form in the wiring conduit will not follow the wires into the oil immersed case.

Other and further objects of my invention reside in the improved construction of momentary contact oil immersed switch as set forth in the following specification as shown in the accompanying drawings in which:

Figure 1 is a top plan view of the oil immersed station showing the momentary contact start-stop switch control; Fig. 2 is a front view of the oil immersed station of Fig. 1 with the tank and a portion of the support thereof broken away and illustrated in section to show the arrangement of contactors and coating contacts within the oil immersed station; Fig. 3 is a fragmentary side elevational view of the oil immersed station of Figs. 1 and 2 with the case and support therefore partially broken away and illustrated in section to show the oil immersed replaceable contactors and replaceable coating contacts in position; Fig. 4 is a vertical sectional view taken on line 4—4 of Fig. 3; Fig. 5 is a fragmentary trans-

2

verse sectional view taken through the movable contactors and coating contacts substantially on line 5—5 of Fig. 2 and line 5—5 of Fig. 4; Fig. 6 is a fragmentary transverse sectional view through the contactor and coating contact system taken substantially on line 6—6 of Fig. 4; Fig. 7 is a plan view partially broken away and illustrated in section showing the arrangement of the fixed coating replaceable contacts in the oil immersed station; Fig. 8 is a reverse plan view of the insulated support for the fixed replaceable contacts illustrated in Fig. 7; Fig. 9 is a transverse sectional view taken on line 9—9 of Fig. 7; Fig. 10 is a side elevational view of a modified form of oil immersed station showing the tank and support therefor in vertical section and illustrating a double arrangement of replaceable contactors and coating replaceable contacts for multiple circuit control as compared to single circuit control in the form of my invention illustrated in Figs. 1—9; Fig. 11 is a transverse sectional view taken on line 11—11 of Fig. 10; Fig. 12 is a vertical sectional view taken on line 12—12 of Fig. 10; and Figures 13A, 13B, 13C, 13D and 13E, show in symbolic arrangement the various types of contacts to which the switch of my invention may be adapted.

Referring to the drawings in detail, reference character 1 represents a plate member which is integrally connected with a housing 2 which is also integrally connected with plate member 3 which extends in a plane normal to the plane of the plate member 1. Plate member 3 is cut away immediately adjacent the housing 2 so that housing 2 has a substantially hollow interior portion 2a within which the actuating mechanism for the contactors may be arranged. The plate member 3 is directly attachable to a standard construction of terminal box 4. Terminal box 4 is provided with securing lugs 4a, 4b, 4c and 4d through which securing means may be passed for anchoring the terminal box to a wall structure. The conduit carrying the electrical conductors to the terminal box 4 terminates in the inlet or entrance sleeve member 5 in one wall of the terminal box 4. Any condensate which may follow the conductors leading into the terminal box 4 will be directed away from the electrical contactor system as such condensate will merely drip to the lower portion of the terminal box 4 at 4e rather than enter the hollow housing 2a. This will be clear by observing the fact that the plate members 1 and 3 extend normally to each other and that the entrance 5 to the ter-

rninal box 4 is located well below the hollow portion 2a of housing 2.

Suitable securing means 6 are provided, passing through plate member 3 and into screw-threaded lug portions of terminal box 4, for securing the plate member 3 in position. The housing 2 is provided with an integrally formed bearing portion 7, through which the shaft 8 is journaled. Shaft 8 projects interiorly into the hollow portion 2a of housing 2 and exteriorly to a position in which the shaft 8 receives the actuator 9. Actuator 9 is provided with a pair of normally disposed pedals or actuating portions 10 and 11 in the form of flat angularly extending plate members. By applying pressure to either of the plate members 10 or 11 shaft 8 may be rocked angularly. Interiorly of the hollow portion 2a of the housing 2, I provide a rocker 12 secured to the shaft 8 by suitable means such as rivet 13. The rocker 12 has oppositely directed extensions 14 and 15 thereon which are arranged to rock simultaneously with the movement of the plate portions 10 and 11 of the actuator 9 for engaging the headed ends 17 and 18 of the plunger members 19 and 20, respectively. The plunger members 19 and 20 extend through the removable screw-threaded bushing units 21 and 22.

The screw threaded bushing units 21 and 22 each have screw threads thereon adapted to removably engage with screw-threaded bores 23 and 24 in plate member 1. The screw-threaded bushings 21 and 22 are each arranged to receive cylindrical members 25 and 26, respectively, formed from insulation material. The cylindrical members 25 and 26 are secured by suitable rivets 25a and 26a to the plunger members 19 and 20, respectively, and move with the plunger members as the plunger members are depressed under control of rocker arm 12. Each plunger member terminates in a headed end of insulation material represented at 27 and 28, respectively. The headed ends comprise a washer member 27 and 28 which are held in position by the collars 27a and 28a integral with the ends of the plunger members 19 and 20, respectively. The headed ends serve as abutments for the conductive disc-like members 29 and 30 which form the electrical conductive means for bridging the sets of contacts which are included in the oil switch system of my inventions. In the case of the plunger member 19, however, the conductive disc 29 has a coil spring 31 interposed between the end portion 27 and the conductive disc 29. In the case of the coacting conductive disc-like member 30 coil spring 32 is interposed between the end of the insulation member 26 and the conductive disc-like member 30. This permits the arrangement of the coacting sets of fixed contactors so that one set of fixed contactors, as represented, for example, at 33 and 34, may be maintained closed while the other set of fixed contactors, as represented, for example, at 35 and 36, may be maintained open in the normal position of the actuator 9, as represented in Figs. 1, 2, 3 and 4.

It will be observed that the plunger members 19 and 20 and their associated removable bushing units 21 and 22 may be readily removed from the plate member 1 for renewal or replacement from time to time. This is accomplished by removing the oil container 71 and unscrewing and removing the bushing units 21 and 22. The movable contactors are thus capable of being readily replaced or renewed by fresh units containing disc-like members with fresh contact surfaces for coaction with the fixed contactors.

The sets of fixed contactors are mounted upon a removable panel structure represented by reference character 37. The removable panel structure 37 is formed from insulation material and is provided with a pair of spaced longitudinally extending insulated shield-like portions 38 and 39. The shield-like insulated portions 38 and 39 of the plate-like members 37 are slotted longitudinally as represented at 38a and 39a. These insulated shield-like portions serve as separators between the contacts of each of the sets of contacts 33-34 and 35-36. It will be observed that the sets of contacts 33-34 are suspended from the panel 37 of insulation material on angle members 40 and 41 which align the contacts 33 and 34 with the conductive disc-like member 29 so that as the conductive disc-like member 29 is moved by plunger member 19 contacts 33 and 34 may be bridged, as represented in Figures 2 and 4, for establishing a shunt electrical connection therebetween or, as in the case of the conductive disc-like member 30, the disc-like member 30 may be displaced from the contacts 35 and 36 for opening the electrical circuit therebetween by displacement of the conductive disc-like member 30 from the contacts 35 and 36. It will be observed that contacts 35 and 36 are mounted on angle members 42 and 43 which depend from the plate 37 of insulation material and with a portion of the shield of insulation material 38 extending therebetween.

The shields of insulation material 38 and 39 are each apertured longitudinally of the length thereof for the passage of the securing bolts 44 and 45 which are screw threaded at the ends thereof into the plate member 1, as represented, for example, in Figure 3 at 44a. By removing the bolt members 44 and 45 the entire fixed contact assembly may be readily removed for renewal or replacement. The angle members 40, 41, 42 and 43 which are secured to the plate member 37 each terminate in binding posts or connecting screws 40a, 41a, 42a and 43a to which connection is made through the wires which are brought through entrance 5, terminal box 4, the hollow interior 2a of housing 2 and through the entrance way 46 in the plate member 1. Thus connection is made to the sets of fixed contacts which may be bridged selectively by angular movement of rocker 12 under control of actuator 9. As represented in Figures 1-4, one set of contactors 33 and 34 is bridged while the opposite set of contactors 35 and 36 remains open. This selective control is effected by pressure applied to either of the panels or plate-like portions 10 and 11 of the actuator 9.

I have shown in Figures 10-12 an arrangement of a double contactor system in which one set of contactors of each group of contactors is bridged while the other set of contactors remains open and in which reverse operation may be obtained by alternate movement of the actuator. In this arrangement there are two sets of removable panels of insulation material which I have represented at 47 and 48, both of which are suspended from the plate member 1 through removable bolts 49 and 50 and 51 and 52, respectively. The panels 47 and 48 each carry coacting sets of bracket members which support coacting contact with which the sets of conductive disc-like members coact. For example, panel 47 carries sets of brackets, 53, 54, 55 and 56, each of which has contactors thereon aligned with the disc-like conductive members controlled by the plunger members 19 and 20. Similarly, panel 48 carries

such brackets 57, 58, 59 and 60 having contactors adjacent the ends thereof aligned with the conductive disc-like members. In the particular arrangement illustrated in Figures 10-12, there are two conductive disc-like members associated with each of the plunger members. In the case of plunger member 19 there is a conductive disc-like member 61 backed by a plate of insulating material 62 and there is also a conductive disc-like member 63 backed by a plate of insulation material 64. These two sets of conductive disc-like members with the sheets or discs of insulation material adjacent thereto are separated by spring member 65 tending to continuously urge the sets of disc-like members apart and toward the coacting fixed contacts. When one set of fixed contacts is bridging the other set of fixed contacts remain open, but as the plunger member 19 is axially shifted to effect the required displacement a coil spring 65 yields to cushion the abutment of the respective conductive disc-like members with respect to the associated fixed contactors. In the case of the plunger member 20 I provide conductive disc-like members 66 and 67 centered upon insulated bushing 68 co-extensive with the cylindrical insulation member 26 with backing discs of insulating material represented at 68 and 69 associated therewith and provided with coil spring 70 located therebetween. Thus, the respective conductive disc-like members may be displaced for establishing alternate connection with either of the coacting sets of fixed contacts depending upon the axial displacement of plunger member 20. The coil spring 70 serves as a yieldable cushioning to prevent shock in establishing connection between the respective conductive disc-like members and the associated sets of fixed contacts.

In Figure 13A I have shown in symbolic form one of the elemental forms of the switch of my invention in which two fixed contacts are normally open and which may be bridged by depressing the plunger member carrying the conductive disc-like member, thus serving to complete electrical circuit across the fixed contacts. In Figure 13B I have shown an arrangement of the switch of my invention in which two fixed contacts are normally closed by bridging relation with the conductive disc-like member.

In Figure 13C I have shown a double pole switch arrangement in which two sets of fixed contacts are bridged normally by two insulatingly arranged disc-like conductive members. Axial movement of the plunger member serves to displace the disc-like members from engagement with the associated fixed contacts for opening the normally closed circuits. In this arrangement the conductive disc-like members are maintained in protected insulated relation to each other by an arrangement similar to that illustrated in Figure 12 in which the conductive disc-like members are spaced upon an insulation material and backed by discs of insulation material.

In Figure 13D I have shown an arrangement of the switch system embodying my invention in which two separate conductive disc-like members are normally maintained in open circuit position with respect to the two sets of fixed contacts. By this arrangement depression of the plunger member serves to move the conductive disc-like members into projecting relation to the associated fixed contacts.

In Figure 13E I have shown in symbolic representation the arrangement illustrated in Figures

10-12 wherein one disc-like member serves to maintain one set of coacting fixed contacts closed while another conductive disc-like member maintains the coacting set of fixed contacts open ready to be alternately controlled by the axial movement of the plunger member.

In all of the several arrangements of the oil switch of my invention I provide a container for oil which is represented at 71 which may be filled with oil to a level well above the conductive disc-like members and the coacting fixed contactors associated therewith, but below the wiring terminals represented, for example, at 40a, 41a, 42a, 43a, etc., which permits ease of wiring the several terminals which have not been subjected to continuous immersion in oil.

The oil container 71 is maintained in position with respect to plate member 1 by suitable securing screws 72 which pass through the top of plate member 1 and enter screw-threaded apertures formed in corner portions 73 of the container.

I have found the oil switch of my invention highly practical in manufacture, production, operation and maintenance. The fact that the contactors, although fixed and movable, may be readily renewed and replaced in the casing for the switch substantially reduces maintenance cost as the casing for the switch system and the actuator therefor are substantially permanent in character, allowing renewal and replacement of those parts which are very readily subject to wear.

The fact that the parts of the switch of my invention may be readily removed, replaced and installed makes it possible for a customer or user to purchase the elemental parts of the switch and make the installation in the field in accordance with the requirements of a particular problem.

While I have described my invention in certain of its preferred embodiments, I realize that modifications may be made and I intend no limitations of my invention otherwise than may be imposed by the scope of the appended claims.

What I claim and desire to secure by Letters Patent of the United States is as follows:

1. An oil switch comprising a casing including a wall member and an attachable cover member therefor, a pair of depressible plunger members removably mounted on said wall members, conductive disc-like members carried by each of said plunger members, a pair of panels of insulation material detachably mounted on said wall member in spacial relation to said plunger members, said panels having insulated projections thereon, extending in planes substantially normal to the planes of said panels, sets of contacts supported with respect to said wall member on opposite sides of the projections on said panel members in the path of said conductive disc-like members, yieldable means associated with said conductive disc-like members and with said plunger members, and means for selectively and alternately displacing said plunger members and conductive disc-like members with respect to said sets of contacts for selectively shunting or disconnecting the respective sets of contacts.

2. An electrical switch comprising in combination a wall structure, pairs of projectable and retractile plunger members detachably mounted on said wall structure, contactors carried by each of said plunger members, panel members of insulation material detachably connectible with said wall structure adjacent said plunger mem-

bers, sets of fixed contacts mounted in spaced positions on said panel members adapted to register with the contactors carried by said plunger members, and barriers of insulation material projecting on either side of said panel members between said sets of fixed contacts for insulating the contacts of each set one from another.

3. A switch structure comprising a wall member, a pair of projectable and retractable plunger members detachably mounted on said wall member, contactors carried by said plunger members, a pair of spaced longitudinally extending shield-like portions of insulation material each having a centrally disposed bore extending therethrough for the passage of securing bolts, detachable securing bolts extending through the bores in said longitudinally extending shield-like portions and detachably connectible with said wall member adjacent the mounting of said plunger members thereon, a panel of insulation material extending between and projecting transversely beyond said shield-like portions of insulation material, and fixed contacts mounted on said panel for registration with the contactors carried by said plunger members and disposed on opposite sides of said shield-like portions with said shield-like portions projecting therebetween and insulatingly separating said fixed contacts.

4. A switch structure comprising a wall member, a pair of projectable and retractable plunger members detachably mounted on said wall member, contactors carried by said plunger members, a pair of spaced longitudinally extending shield-like portions of insulation material each having a centrally disposed bore extending therethrough for the passage of securing bolts, detachable securing bolts extending through the bores in said longitudinally extending shield-like portions and detachably connectible with said wall member adjacent the mounting of said plunger members thereon, a panel of insulation material extending between and projecting transversely beyond said shield-like portions of insulation material, said panel having the peripheral edge thereof spaced from said wall member for the passage of connecting conductors, and fixed contacts mounted

on said panel for registration with the contactors carried by said plunger members and disposed on opposite sides of said shield-like portions with said shield-like portions projecting therebetween and insulatingly separating said fixed contacts and terminals for said fixed contacts located adjacent said peripheral edge of said panel for establishment of connection with conductors extending between said peripheral edge and said wall member.

5. A switch structure comprising a wall member, a pair of screw-threaded removable bushings extending into said wall member and terminating in cylindrical cup-like guides, spring actuated plunger members extending through said bushings and terminating in actuating heads on one end and sleeves of insulation material on the other end, said sleeves of insulation material having the ends thereof slidable in said cylindrical cup-like guides, movable contactors mounted on the other ends of said sleeves and fixed contacts insulatingly supported with respect to said wall member and aligned with said movable contactors and operative to establish connection therewith, and means engaging the actuating heads on said plunger members for controlling the connections between said movable and fixed contacts.
